UNITED STATES PATENT OFFICE

2,038,406

MECHANISM FOR PRODUCING CARTONS

Leon Benoit, New York, and E. Joseph Kanabay,
Nyack, N. Y.; said Kanabay assignor to said
Benoit

Original application March 1, 1933, Serial No.
659,128. Patent No. 1,970,550, dated August
21, 1935. Divided and this application June 21,
1934, Serial No. 731,617

7 Claims. (Cl. 164—90)

The mechanism of the present invention, heretofore disclosed in an application filed March 1, 1933, under Serial No. 659,128 of which this case is a division) is designed primarily for the purpose of die-cutting once folded blanks forming the body of an egg carton of the general kind set forth and described in Letters Patent No. 1,768,023, issued June 24, 1930, to Leon Benoit.

10 In cartons of this character it is customary to construct the body of the carton from a single sheet of paper board which is folded upon itself along a medial score line forming a blank of double thickness; the blank so folded is then 15 slotted and punched to provide openings through which cross partitions are inserted. Inasmuch as the folded blank is of double thickness, a single operation of punching will suffice to produce in the two thicknesses openings which are aligned 20 and identical.

The present invention also has to do with the folding of the two halves of the blank about the medial line of fold while being fed into the die mechanism, as well as means for centering and 25 properly locating the once folded blank with reference to the cutting blades of the die-cutting mechanism.

Further details will appear from the description of the invention in conjunction with the accompanying drawings, wherein,—

Figure 1 is a view in side elevation of the machine in its entirety;

Fig. 2 is a perspective view of an assembled carton made from a blank which has been die-cut in the present machine;

Fig. 3 is a view of the blank, folded upon itself and die-cut in accordance with the present invention;

Fig. 4 is a partial plan view of the machine as viewed on line 4—4 of Fig. 1;

Fig. 5 is a sectional elevation view, the section being taken on line 5—5 of Fig. 1;

Fig. 6 is a view of the face of the die as shown on line 6—6 of Fig. 4;

Fig. 7 is an enlarged fragmentary view in section taken on line 7—7 of Fig. 6; and

Fig. 8 is a view in perspective showing the relation between the die-cutting heads, the diverging guides and the feeding arm

50 The various operations involved in the present mechanism have to do with the folding and dieing of carton blanks *p* made desirably of suitable paper material, in preparation for the reception of the cross walls in conformity with a scheme 55 of assembly not here shown. The carton blanks

in flat unfolded form are first introduced into the mechanism in the form of a vertical stack arranged within a hopper *A*. It is customary to first print the carton blanks with the intended designations and provide them with a series of longitudinal score lines or ribs, as indicated in Figs. 2 and 3. The carton blanks in flatwise position are fed forward through rollers *B* into a bender *C* in the nature of a press which breaks down the blank along the score lines. 10

The mechanisms just referred to are shown and described in detail in Letters Patent No. 1,970,950, issued under date of August 21, 1934, and need not be described again in detail, inasmuch as we are here concerned particularly with 15 the die-mechanism *D*.

The blank is first folded to V-form along a medial score line *a*. Each of the halves of the blank lying on opposite sides of the medial line of fold *a* is also bent along similar score lines *b*, 20 *c*, *d*. When erected to final position, each half of the blank is in the form of a trough with the score line *b* constituting the inverted ridge of the carton, with the section *e* subtended between the score lines *b* and *c*, constituting an oblique outer 25 wall, with the section *f* subtended between the score lines *c* and *d* constituting the top, and with the marginal section beyond the score line *d* constituting a flap to tuck in for the purpose of closing the carton. 30

While being acted upon by the breaker mechanism *C*, the carton blank is medially folded and thereafter advanced to the die-punching mechanism *D*. Here it is subjected to the action of dies that cut out certain vertical slots *g* which traverse the score lines *b* so that each of the two opposite sections of the carton blank will be similarly punched. Simultaneously, the medial score line *a* is died to cut out half-circular notches *h* 40 which appear as circular holes in the flattened blank. 45

From the die-punching mechanism, the carton blanks are fed forwardly in edgewise relation to a stacker *E* within which the carton blanks are 50 compressed into a horizontally extending stack with the folded carton blanks standing on their folded edges, as indicated at the right of Figs. 1 and 4.

All the mechanisms, *A*, *B*, *C*, *D*, *E*, are carried 55 upon a table *I* supported upon corner legs *II* at a convenient height above the floor. Suspended beneath the table is a drive shaft *12*, driven by an electric motor *13* as by means of a sprocket chain *14*. A second shaft *15*, placed per-

pendicular to the drive shaft 12, is driven therefrom as by means of beveled gears 16 and 17.

Each blank is ejected from the bending mechanism C, its lower edge is caught by rollers 18 which are driven by the shaft 12 through suitably entrained driving connections, not shown, and fed forward to the die press D. Rollers 19 cooperate with rollers 18 in feeding forward the carton, which, it will be noted, is folded so that 5 the wing portions lie adjacent each other during its advance forward by the pairs of rollers 18 and 19. It is necessary in feeding the blanks forward that the wing portions of the carton blanks be lifted as they are advanced into the 10 die press, as indicated in dotted lines in Fig. 1, and to effect this result a pair of converging obliquely disposed guide bars 20 are provided. These guide bars extend obliquely upward to a 15 plane above the level of the die press and terminate in horizontally extending guide portions 21, which are closely spaced and extend in parallel relation and are upturned at their forward ends at 22. The advancing blanks are thus folded into flatwise relation as they enter the die press 20 and stand vertically upon the medial score line a which constitutes the folding line of the blank. The rollers 18 and 19 serve to impart the necessary impetus to carry the folded blanks forwardly to substantially the position indicated in Fig. 6, 25 but this impetus has a tendency to slightly tilt each blank obliquely, as in Fig. 6. In order to accurately position the blanks to receive the die cuts, the following mechanism is provided:

A stop block 23 is located in position to engage 30 the folded blank near its forward lower corner when projected upwardly into the full line position shown in Fig. 6, and to release the blank when the block is depressed to the dotted line position. The stop block 23 is carried by a vertical 35 bar 24, the lower end of which is actuated by a cam 25 on the longitudinally extending cam shaft 15.

The stop block 23 coacts with a swinging arm 26 carried by a head 27 mounted upon the upper 40 end of a vertical shaft 28 which extends through a stationary journal standard 29, which standard is provided near its upper end with an outstanding bracket segment 30, which affords a 45 guide rest for the arm 26 which swings from the full line position to the broken line position shown in Fig. 4.

The swinging arm 26 at its free end carries a finger 31 (see Fig. 7) of channel formation which embraces the tip end of the arm and is 50 pivotally mounted upon a pintle 32. The finger extends beyond the arm, and its inner end terminates in a tail piece 33 to which is secured a coil spring 34 which normally serves to hold the channel shaped finger rearwardly into contact with a plunger 35 backed by a spring 36 (see Fig. 7). The finger is positioned to ride upon the horizontal guide bars 21, and on its advancing movement to ride upwardly upon a pair of elevated shoes 37, and the amplitude of movement imparted to the arm is sufficient to carry the finger 31 beyond the shoes 37, after which sufficient freedom of movement is afforded in the mounting for the arm 26 to permit the spring-pressed draw pin 37a to draw down the arm sufficiently to bring the finger below the level of the proximate shoe, so that on the return movement of the parts the finger will ride against the proximate side wall of the shoe, as indicated in dotted lines in Fig. 7, thereby permitting the finger to 65 return without bridging across the slot between

the guide bars 21, so that, although the finger is positioned to assist, on its forward movement, in advancing a carton blank to position within the die press, it will not thereafter, on its return movement, interfere with the progress of the next 5 oncoming blank between the guide bars 20-21.

As shown in Fig. 8, the guide finger 31 is provided with a prong 38 which on the forward movement overlies the upper exposed edge of the carton blank (see Fig. 6) at the same time 10 that the finger presses against the rear edge, and these two contacts in unison serve to impart a downward and forward thrust at the upper rear corner of the carton blank, and this thrust together with the downward movement of the block 15 23 causes the carton blank to settle down from the tilted position shown in Fig. 6 into the level position occupied during the die-cutting operation. While the blank is being punched, the block 23 is further moved downwardly to occupy 20 a position below the line of movement of the blank after the same has been punched.

The die press comprises a vertically standing backing frame 39 provided with a base flange 40 and a top flange 41, and the backing frame has 25 secured thereto a face plate 42 which is provided with a level shoulder 43 which furnishes a ledge upon which the base edge of the folded carton blank rests during the dieing operation. The base portion of the plate has bolted thereto an 30 upstanding front plate 44, which above the shoulder 43 stands in spaced relation to the face plate 42 to afford a deep narrow channel for the passage of the carton blanks, and to strip the blank from the dies.

The dieing out of the slots in the folded carton blanks is performed by a group of vertically disposed spaced saw toothed die members 45 which operate through slots 46 and 47, respectively, in the front plate 44 and the face plate 42. The 40 resulting cutting is a shearing rather than a punching operation. The half-circular notches in the folded base edges of the carton blanks are cut by die members 48 operating through slots 49 and 50, respectively, in the front plate and 45 the face plate. If desired, upper cuts in alignment with the slots may be formed by a die member 51 operating through openings 52 and 53, respectively, in the front plate and face plate (see Fig. 5).

In order to afford sufficient amplitude of movement to the die members, the backing frame 39 is likewise provided with openings which register with and constitute continuations of the openings in the face plate. The die members are carried 55 by a block 54 secured to the inner face of a longitudinally extending rocking bar 55 provided with brackets 56 mounted upon a shaft 57, the axis of which lies within the plane occupied by the carton blanks during the dieing operation. 60 As shown, the die members and slots through which they operate are arcuately configured to allow for the slight arcuate movement imparted by a rocking of the bar 55 on its shaft 57.

The bar 55 has depending therefrom an arm 65 58, the lower end of which has pivoted thereto the inner end of a pitman 59, the outer end of which is pivoted to a lever 60 pivoted on a pintle 61 carried by a bracket 62 on the forward side of the table, and a rocking motion is imparted to the 70 lever through the medium of a pitman 63 slotted at its inner end to embrace the shaft 15. The pitman 63 is provided with a roller 64 which engages a cam 65 carried by the shaft 15, so that rocking motions are imparted to the bar 55 at 75

timed intervals. The cuttings removed during the dieing operation are discharged into a chute 66 and removed from the machine.

In order to assist in guiding the carton blanks 5 to position and in holding them during the die-cutting operations, spaced wing plates 67—67 are mounted above the guide bars 21, and on opposite sides of the guide slot between the plates, and in order to prevent lifting or tilting of the blanks, 10 an overhanging guide plate 68 having a tail piece 69 is provided (see Fig. 8), which members are carried by a post 70 upstanding from the backing frame 39. The post 70 also serves as a means for supporting the inner ends of the guide bars 15 21, one of the bars being supported directly by the post and the other being supported through a spacer pin 71 depending from the overhanging guide plate 68.

Fig. 4 shows the die bar 55 swung back to expose 20 the inner face with the cutting die members 45 retracted sufficiently to permit the insertion of a carton blank. As the die closes, the bar 55 will swing from the oblique position indicated in Fig. 4 to the vertical position indicated in Fig. 5. During 25 the dieing operation, the swinging arm 26 which carries the finger 31 occupies the intermediate position indicated in dotted lines in Fig. 4, but after the conclusion of the dieing operation, the arm 26 moves forward to the right hand 30 dotted line position to feed the blank out of the dies. It will be noted that during this last feeding movement, the stop block 23 is at rest in a downward position indicated by the dotted line shown in Fig. 6. Thus the blank is permitted to 35 move forwardly under the thrust of the swinging arm.

The movements of the arm 26 are controlled by the action of a cam 72 carried by the cam shaft 15 which operates on the lower end of the vertical 40 rock shaft which carries the arm and imparts first a feeding movement into the die cutters, and after a period of rest a short terminal movement to discharge the died blanks and move them forwardly into the bite of a pair of power rollers 45 73—73, which feed them forwardly into the stacker E. The movement of the stop block 23 is likewise controlled by a cam 25 in timed relation to the feeding and discharging movements of the swinging arm (see Fig. 1).

50 The stacker E is horizontally arranged and comprises a pair of spaced rails 74 of angle formation, one of the rails being provided with a flared mouth 75 to receive the folded blanks standing edgewise in position to be actuated by a plunger 76 carried by guide rods 77 operating through guides 78. A cross head 79 connects the guide rods 77, and a pitman 80 serves to reciprocate the cross head. The pitman is pivoted at the upper end of a lever 81 (see Figs. 1-4) which 55 is pivoted on a pintle 82 and is operated by a cam 83. The initial reciprocation of the plunger carries it past a pair of swinging spring-pressed stops 84—84 which yield under the pressure of an incoming carton blank but prevent return thereof, so that by the repeated reciprocations of the 60 plunger, a stack of cartons standing vertically edgewise is deposited within the guideway afforded by the rails 74.

In order to positively and evenly position the 70 carton blanks delivered from the rollers 73, a swinging arm 85 is provided which is mounted upon a vertical rock shaft 86 and is actuated from the full line position shown in Fig. 4 to the dotted line position. The rock shaft 86 is actuated by a cam 87 on the cam shaft 15.

This completes the series of operations performed in the mechanism which finally stacks the cartons in form to be removed and delivered to the mechanism provided for inserting the cross walls through the slots and folding and delivering the cartons in a completed knock-down condition.

In operation, the printed and scored blanks are successively fed from the stack through the rollers B to the breaking mechanism C, and at this point are bent along the spaced parallel scoring lines to provide a medial V-shaped body portion with outstanding wing portions on either side thereof. From the breaking mechanism the once folded blanks are fed by the rollers 18 and 19 through 151 the converging guide bars 20 where the wing portions will be engaged and progressively lifted or bent upwardly into flatwise relation to one another in preparation for the entry of the blank into the die mechanism D, so that during the die-cutting operation the blank will stand in once folded relation to receive the corresponding die cuts through the two plies of the blank, as well as the half-circular notches in the folded base edge thereof.

In preparation for the die-cutting operation, the blank will be properly positioned by the combined action of the stop block 23 and the spring-pressed finger 31, and after receiving the die cuts, the blank will be further advanced by the terminal swing of the arm 26 to bring the forward vertical edges of the blank into the bite of the rollers 73 which advance the folded and died blank to the stacker E within which it is positively positioned by the swing of the kicker arm 85.

We claim:

1. In a die-cutting mechanism for carton blanks, the combination of a fixed die having openings therein, a shoulder formed on the die for supporting the blank, a punching head hinged to the die and adapted to cooperate therewith in punching the blank, a movable stop positioned in the plane of the shoulder and normally positioned thereabove to stop the incoming blank, the stop being retractable below the level of the shoulder to position the blank thereon and to permit ejection of the blank across the top of the stop after the blank has been punched.

2. In a die-cutting mechanism for carton blanks, the combination of a fixed die, a punching head movable relative to the die, guide means for the incoming blank, an arm adapted to move the blank to final position within the die-cutting mechanism, and a cam for deflecting the end of the arm out of the path of the next oncoming blank.

3. In a die-cutting mechanism for carton blanks, the combination of a fixed die, a punching head movable relative to the die, guide means for an incoming blank, an arm adapted to swing in a plane perpendicular to the plane of the blank, a finger pivoted to the end of the arm extending therebeyond into the plane traversed by the incoming blank, and a cam on the guide means positioned in the path of the finger which permits the latter to move the blank to dieing position and thereafter swing the finger out of the plane of the oncoming carton.

4. In a die-cutting mechanism for carton blanks, the combination of a fixed die, a punching head movable relative to the die, guide means for incoming blanks, an arm swingable in a horizontal plane traversing that of the incoming blank, the arm having an interrupted movement whereby it is first moved to advance the blank to

position for die-cutting and thereafter to move the die blank from die-cutting position.

5. In a die-cutting mechanism for carton blanks, the combination of a fixed die, a swingable head carrying a punch adapted to cooperate with the die in punching the blank, a movable stop positioned between the punch and die and normally positioned in the path of an incoming blank, a swingable arm for advancing a blank 10 into the die mechanism and against the stop and for yieldingly holding the blank thereagainst while the stop is moved to a position out of the path of the blank in timed relation with the swinging movement of the punching head.
- 15 6. In a die-cutting mechanism for carton blanks, the combination of a fixed die, a swingable head carrying a punch adapted to cooperate with the die in punching the blank, a movable stop positioned between the punch and die 20 and normally positioned in the path of an incoming blank, guide means by which the incoming blank is guided between the punch and die, feeding means including a swingable arm, a yieldable finger pivoted to the end of the arm and 25 adapted to engage the blank and feed it into the die-cutting mechanism and against the stop, the

swingable arm having an initial movement for advancing the blank and a final movement for partially ejecting the blank after die-cutting, and a shoe on the guide means for lifting the finger during its final movement, the shoe being of such a length that the finger will be drawn down beyond the end thereof at the end of its final movement so that as the arm swings in the opposite direction the finger will ride against the proximate side wall of the shoe and out of the path 10 of the next oncoming blank.

7. In mechanism of the class described, the combination of a fixed die having openings therethrough, a punching head pivotally connected to the die, an arcuate punch secured to the punching head in register with the opening in the die, the forward edge of the punch being notched to provide a shearing edge which cooperates with the opening in the die, means for rocking the punching head whereby the punch is alternately 20 moved from punching to withdrawn position, and means for feeding and centering a blank between the punch and die in timed relation to the movement thereof.

LEON BENOIT.
